UNITED STATES PATENT OFFICE.

WENDEL SIMEK, OF GUTTENBERG, NEW JERSEY.

CANE, UMBRELLA, OR THE LIKE.

Application filed April 9, 1926. Serial No. 100,809.

This invention relates to canes, umbrellas and parasols, and the purpose of the invention is to incorporate in cane, umbrella or parasol construction a receptacle suitable 5 for employment as a vanity case or purse or both combined.

In my Patent No. 1,526,246, issued February 10, 1925, there is disclosed a combination cane and handbag, so constructed that 10 it may be associated with a conventional cane, umbrella or parasol by slipping the shaft of the cane or umbrella handle through an attaching member forming part of the bag and without dismantling the cane or umbrella. 15 In other words, the structure of my prior patent embodies an attachment to conventional umbrellas and canes.

The present invention, in contradistinction, embodies a cane, umbrella or parasol, so 20 constructed that the receptacle to which I have referred constitutes an inherent part of the construction, and the associated umbrella, cane or parasol elements are so constituted as to cooperate with such receptacle 25 for the formation of a complete and unitary article of manufacture.

Speaking generally, the present invention embodies a receptacle of dimensions, shape and size appropriate to the particular use 30 to which it is to be put and preferably provided with one or more hinged covers by which access to the interior of the receptacle may be had. At its top and bottom, the receptacle is provided with two relatively rigid 35 attaching parts, the upper one of which is adapted to be secured to the handle of the umbrella, cane or parasol, while the lower of which is adapted to be secured to the shaft of the umbrella, cane or parasol, so that 40 when all the parts are assembled, the receptacle forms a connecting link between said handle and shaft and becomes an inherent part of the cane or umbrella construction.

It is of particular importance that the attaching members at the top and bottom of the receptacle be relatively rigid with respect 45 to one another, since, in the absence of such construction, there would be lack of rigidity between the handle and shank of the article 50 which would seriously interfere with the use of the article for its intended purposes.

In one of its practical forms, the receptacle is provided at its top and bottom with 55 complementary male and female attaching means, the handle of the cane or umbrella being provided with attaching means comple-

mentary to the attaching means at the top of the receptacle, and the shank of the cane or umbrella being provided with attaching means 60 complementary to the attaching means at the bottom of the receptacle. The receptacle serves to rigidly connect the upper and lower attaching means thereto, so that when the handle is secured to the top of the receptacle and the shank to the bottom 65 of the receptacle, the article is rigid throughout.

With this construction, moreover, it is possible to disconnect the handle and shank from the receptacle and directly connect the 70 handle to the shank so as to leave out the receptacle in the event of breakage or damage thereto.

I find it entirely practical and efficient to 75 provide threaded connections between the parts to permit them to be readily assembled or dismantled and I further find it practical to provide a separate handle which may be secured to the receptacle for the purpose of using such receptacle as a handbag or 80 vanity case exclusively of the umbrella or cane. This is not, however, its normal function, it being intended primarily for use with a cane, umbrella or parasol.

The advantage of the construction described is that the receptacle affords convenient means for the carrying of toilet articles, change, etc., and the fact that the shank does not extend through the receptacle 85 provides for maximum space for the reception of such articles as it may be desired to carry therein.

Features of the invention, other than those adverted to, will be apparent from the hereinafter detailed description and claims, when 90 read in conjunction with the accompanying drawings.

The accompanying drawings embody different practical embodiments of the invention, but the constructions therein shown are 100 to be understood as illustrative, only, and not as defining the limits of the invention.

Figure 1 is an elevation showing a cane embodying the present invention, with the parts thereof in assembled relation.

Figure 2 is an enlarged elevation with the parts dismantled and illustrating a portion of the handle and shank of the cane in section.

Figure 3 is an edge elevation of the receptacle portion of the assembly showing the body of the receptacle in central section and

hinged covers with which it is provided, in open position.

Figure 4 is a section on the line 4—4 of Figure 2.

5 Figure 5 is a transverse section corresponding to Figure 4 through a receptacle frame of modified construction.

10 Figures 6 and 7 are side elevations, partly in section, of adjuncts adapted to be associated with the receptacle for the purpose of transforming it into a handbag, when removed from the handle and shank of the cane; and,

15 Figure 8 shows a handbag embodying the receptacle when associated with the adjuncts illustrated in Figures 6 and 7.

20 As hereinbefore stated, the present invention is adapted for use in cane, umbrella or parasol construction. For the purpose of illustration, however, I have shown it as embodied in a cane and without further reference to its general application, I will describe the cane construction, it being understood that the invention is not limited in this 25 regard.

By reference to the drawings, it will be noted that 1 designates the receptacle portion of the cane, 2 the handle portion and 3 the shank portion. The receptacle portion 1 30 embodies a frame 4 which, in practice, may be of any suitable shape or configuration and of a size appropriate to the particular use to which the receptacle is to be utilized.

35 As shown in the drawings, the frame is of rigid construction and to insure absolute rigidity, the frame is provided at both of its faces with inwardly extending flanges 5 which serve to impart pronounced rigidity to the structure.

40 Associated with the opposite sides of the frame are hinged covers 6 and 7 adapted to be locked in closed position by suitable catches 8 and 9 respectively. In the embodiment of the invention shown, the receptacle 45 is adapted to constitute a purse and vanity case and to this end, the cover 6 is provided on its interior with a plate 8 having openings 9 and 10 to support powder and rouge compacts and said plate is further formed, as 50 shown at 10, to support a lip stick 11. The inner side of the cover 7 is provided for a portion of its height with a transverse plate 12 to provide within the cover a pocket 13. On this plate a mirror may be mounted if 55 desired.

60 The interior of the frame 4 is left unencumbered and is adapted to receive any suitable small articles which it may be desired to deposit therein. Formed rigid with the top and bottom of the frame are bosses 14 and 15, respectively. The upper boss 14 is 65 interiorly threaded and the lower boss 15 is exteriorly threaded, these threaded portions being of complementary dimensions.

35 The handle portion 2 of the cane is pro-

vided at its bottom with a male projection 16 adapted to screw into the boss 14, while the neck 3 of the cane is provided at its top with a female threaded sleeve 17. The parts are so proportioned that the threads of the 70 sleeves 17 are the same as the threads in the boss 14, while the threads on the projections 16 are the same as those of the boss 15 for reasons hereinafter and more fully explained. 75

Under normal condition of the parts, the projection of the handle 2 is screwed into the boss 14 and the sleeve of the shank 3 is screwed on to the boss 15 for the purpose of rigidly uniting the component parts of the 80 structure after the manner as shown in Figure 1. The cane is adapted in this condition for its usual purposes, but in addition thereto it embodies, as stated, a neat and compact vanity case and purse which is not only ornamental and æsthetic, but highly useful. 85

If for any reason, it is desired to use the cane without the receptacle or to employ the receptacle as a handbag without the cane, the handle 2 and shank 3 may be disconnected from the receptacle and directly connected to one another, and the receptacle may be thereupon associated with the adjuncts shown in Figures 6 and 7 to form the handbag illustrated in Figure 8. Thus, as shown in Figure 6, a screw plug 18 provided with a suitable handle loop 19 is provided. This plug is of a size and shape to screw into the boss 14 at the top of the receptacle and form a handle therefor. 90

95 In Figure 7 I have illustrated a tassel 20 formed on a threaded sleeve corresponding in construction to the sleeve 17 and this may be screwed upon the boss 15 to conceal the boss and produce a finished appearance to the receptacle when employed as a handbag. 100

105 I have hereinbefore referred to the necessity of making the bosses 14 and 15 relatively rigid. In the preferred form of the invention, this is accomplished by constructing a receptacle with a rigid frame. In the construction of Figures 3 and 4, rigidity is imparted to the frame by forming the flanges 5 thereon. In Figure 5, however, a 110 modified form of frame is illustrated. Here the flanges 5 are omitted and in lieu thereof a transverse partition 5^a is positioned within the frame 4^a to impart the desired rigidity thereto. The rigid frame is found highly 115 satisfactory in practice, but inasmuch as the relative rigidity between the parts 14 and 15 may be obtained in other ways, I do not specifically limit the invention thereto. 120

125 In practice, the receptacle may be conventionally constructed from sheet metal and may be formed in either the base or precious metals, as may be desired, and exteriorly ornamented as preferred.

130 The drawings show the receptacle as provided with two covers and constructed to

function as a combined purse and vanity case. I wish it understood, however, that the invention is not restricted to such an arrangement. It may be in the form of a vanity case only or a purse only, and the particular formation or number of covers, or the particular shaping of the frame may be varied without departing from the spirit of this invention, which is to be understood as fully commensurate with the appended claims.

In referring to cane in the following claims, I wish it understood that this word is synonymous to umbrella and parasol, so far as the scope of the claims is concerned.

Having thus fully described the invention, what I claim as new and desire to secure by Letters Patent is:

1. A cane or the like embodying a handle, a shank and a vanity case positioned intermediate the handle and the shank and secured to both of said parts for rigidly uniting the handle and shank, the handle and the shank being constructed to be detachably directly united with the vanity case omitted, said vanity case having a door in the side through which access to the interior of the case may be had.

2. A cane or the like embodying a vanity case provided in its side with a door through which access may be had to the interior of the case, a handle detachably secured to the top of the case and extending upwardly therefrom, and a shank secured to the bottom of the case and extending downwardly therefrom, the shank and handle being constructed for direct union to form a complete cane.

3. A cane or the like embodying a handle, a shank, and a hollow receptacle positioned

intermediate the handle and shank and rigidly uniting said parts, said receptacle being provided at its side with a door through which access may be had to the interior of the receptacle and said receptacle being of appreciably greater cross sectional dimensions than either the handle or the shank, the handle and shank being operatively connectible to form a complete cane when the vanity case is removed.

4. A cane or the like embodying a handle and a shank, the contiguous ends of which handle and shank are provided with complementarily threaded male and female attaching members, a vanity case provided in its side with a door and having at its top and bottom threaded male and female attaching members complementary to the corresponding members of the shank and handle whereby the handle may be screwed to the shank directly or may be secured thereto by securing the handle to the vanity case and the vanity case to the shank.

5. In a cane or the like, a handle and a shank, the contiguous ends of which handle and shank are provided with complementary attaching means, and a receptacle provided at its top and bottom with attaching means complementary to the attaching means of the handle and shank, whereby the handle and shank may be secured either together directly or may be secured to one another by attaching the shank to the bottom of the receptacle and the handle to the top of the receptacle.

In testimony whereof I have signed the foregoing specification.

WENDEL SIMEK.
